UNITED STATES PATENT OFFICE.

EDWARD S. STANTON, OF CLEVELAND, OHIO.

BUILDING BLOCK OR TILE.

1,088,040.

Specification of Letters Patent.

Patented Feb. 24, 1914.

Application filed September 18, 1913. Serial No. 790,484.

To all whom it may concern:

Be it known that I, EDWARD S. STANTON, a citizen of the United States, residing at Cleveland, in the county of Cuyahoga and 5 State of Ohio, have invented certain new and useful Improvements in Building Blocks or Tiles; and I do hereby declare the following to be a full, clear, and exact description of 10 the invention, such as will enable others skilled in the art to which it pertains to make and use the same.

This invention relates to building blocks or tiles employed for the construction of walls, the object being the production of a 15 block or tile which is simple in construction, easily bonded and provided with interlocking means on its upper and lower surface.

A further object of this invention is to 20 produce a tile or block which provides a wall structure forming a plurality of independent air chambers extending in a horizontal direction, the blocks being formed with projections and mortar receiving spaces into 25 which the projections of an adjoining block are received thus forming a structure which prevents moisture from passing from one face of the wall to the other.

A still further object of the invention is to 30 so form the block or tile that the same may be easily dressed while being set or laid.

This invention consists in the peculiar construction of the tile or block as will be hereinafter fully set forth and claimed.

In the drawings Figure I, is a perspective 35 view of the block embodying this invention, and Fig. II, is a section taken through a portion of the wall illustrating the manner in which the blocks or tiles are assembled or 40 laid and the manner of engaging the same with each other by means of mortar or cement.

The construction of the tile or block is as follows: The hollow chambers 1, and 2, are 45 provided on each side of the block and are bonded at the top by a suitable web. At the lower inner corners of each chamber projections 7 and 8 are provided and at the upper outer corners of said chambers projections 3 and 4 are provided, all of the above 50 named projections being undercut in opposite directions thus forming dove tailed projections. The web 6 which connects the two chambers 1 and 2 is provided on the upper surface with a dove tailed projection 5.

55 For reasons hereinafter set forth this dove

tailed projection 5 is slightly higher than the upper surface of the tile proper and the upper edge of said projection 5 is squared as at 9". By forming a brick in the above manner the projections 3 and 4 in combination with the projection 5 provide a series of recesses 9 and 10 into which fit the lugs of an adjoining brick. In utilizing this brick for building purposes the mortar 9' is placed upon the upper surface of the brick 60 (not necessarily on the upper surface of projection 5) and in the recess 9 and 10; the next brick is then placed on top of the brick thus prepared and the projections 7 and 8 placed in the grooves 9 and 10, thus forming 65 another air chamber 6'. By constructing the brick with the projection 5 higher than the surface of the brick proper the mortar 9' can be placed on the brick easily without covering the top of the projection 5 and further this construction of the projection 5 70 provides a more positive anchorage for the brick with the adjoining one.

The object of squaring the projection 5 as 75 at 9" is to allow the base of said projection 5 being made heavy while at the same time allowing the top of said projection being made small enough to pass between the projections 7 and 8 of the adjoining brick and allows the brick to be dressed or moved in 80 relation to the adjoining brick. From the above it will be seen that a wall constructed of this brick provides independently spaced and non-communicating horizontal chambers 1 and 2 and 6' and it will also be noted 85 that the mortar which binds the bricks is so placed and utilized that while the courses are firmly bonded or tied together the mortar does not continue from the outer surface to the inner surface of the brick and hence 90 moisture can not penetrate from surface to surface through the medium of the mortar. It is further seen that a brick of this structure allows a greater surface to be covered 95 by the mortar thus forming a more perfect and solid joint or connection of the bricks.

In setting forth and describing this invention I have shown a brick as I believe is best adapted for the general use of building but it is apparent that the shape, size and contour of the bricks may be varied to suit the requirements and still the objects of my invention be retained.

What I claim is:

1. A block or tile of the class described 110

comprising two chambers located at the outer edge thereof, undercut projections located on the upper surface of the said chambers, said chambers being connected by means of a web, said web being provided on its upper surface with a dove tailed projection extending above the normal level of the block proper, said undercut projections and said dove tailed projection combined forming recesses directly above the inner walls of said chambers, the lower edge of said inner walls being provided with dove tailed projections adapted to fit into the recesses of an adjoining brick, all substantially as and for the purpose set forth.

2. A block or tile of the class described comprising two chambers located at the outer edge thereof, projections located on the

upper surface of said chambers, said chambers being connected by means of a web, said web being provided on its upper surface with a projection, said projections combined forming recesses directly above the inner walls of said chambers, the lower edge of said inner walls being provided with projections adapted to fit into the recesses of an adjoining block or tile, all substantially as and for the purpose set forth. 20 25

Signed at Cleveland in the county of Cuyahoga and State of Ohio this 13th day of 30 September 1913.

EDWARD S. STANTON.
